UNITED STATES PATENT OFFICE.

GUSTAV BAUM, OF BRESLAU, GERMANY.

TAXOMETER OR FARE-INDICATOR.

No. 820,281.

Specification of Letters Patent.

Patented May 8, 1908

Application filed August 3, 1905. Serial No. 272,612.

To all whom it may concern:

Be it known that I, GUSTAV BAUM, a subject of the King of Prussia, German Emperor, residing at Breslau, Germany, have invented 5 certain new and useful Improvements in Taxometers or Fare-Indicators, of which the following is a specification.

This invention relates to taxometers or fare-indicators, the adding or counting mechanism of which does not start working until the vehicle with which the apparatus is connected has traversed a distance corresponding to the minimum standard fare to be charged or until an equivalent amount of 15 time has been consumed by waiting after the vehicle has been hired. In the apparatus of this kind hitherto known the devices used for locking and unlocking the counting or adding wheels were not sufficiently reliable in their 20 action, so that inaccurate results were frequently indicated, this being more particularly due to the fact that a lever movement of considerable extent was required to operate the said devices and that the latter were not 25 properly secured in their operative and inoperative positions.

According to the present invention these disadvantages are obviated by using a controlling mechanism adapted to be operated 30 with perfect precision by a comparatively very small movement of the controlling-lever, the said mechanism being effectually prevented from engaging the distance or time transmission mechanism while the "minimum-fare" distance is being traversed, or 35 while an equivalent amount of time is being consumed by waiting. When the said distance has been traversed or the said amount of time has been consumed, the transmission-lever is immediately thrown into gear with 40 the counting mechanism, and means are provided for returning the said lever and the said mechanism to their original and normal positions when the hire of the vehicle expires. 45 When the counting mechanism is in its normal position, it indicates the minimum standard fare.

The invention is diagrammatically illustrated in the annexed drawings, in which—

50 Figure 1 is an elevation of part of the mechanism in its inoperative position. Figs. 2, 3, and 4 represent the same mechanism in various operative positions. Fig. 5 is a plan of the indicating mechanism in partial section. 55 Fig. 6 is a detail view. Fig. 7 is an elevation of the mechanism to the rear of that shown in

Fig. 1 as seen from the back. Fig. 8 is a side elevation thereof.

The mechanism comprises a train of levers 4, 8, and 13, arranged in a box 12, the lever 60 13 carrying a pivoted dog 2, adapted to be brought into engagement with an operating ratchet-wheel 1, which is driven by suitable means while the vehicle is traveling or waiting after hire—for instance, by means of an 65 air-pump in the former case and by means of clockwork in the latter. The lever 4 is pivoted at 5 and is provided with a pin 6, which engages a recess 7 in the lever 8, the latter being pivoted at 9. A disk 10, screwed to the 70 lever 8, is adapted to engage a recess in the lever 13, which is pivoted at 11. A ring 49, fixed to the back of the box 12, supports the adjacent ends of the levers 8 and 13 when in their lower position, Figs. 2 and 3. A spring 75 21, attached at opposite ends to a pin 16 on the lever 13 and to the back of the box 12, respectively, tends to pull the said lever toward the ratchet-wheel 1 to bring the dog 2, which is pivoted to the said lever at 14, into engagement with the said ratchet-wheel.

A cam 3, acting on the tail of the lever 4, is operated by an exterior handle 150 and when in the position shown in Fig. 1 holds the levers 4, 8, and 13 in such a manner as to extend 85 the spring 21 and move point 17 of the dog 2 out of engagement with the ratchet-wheel 1. In order to lock the dog 2 in its operative position and to allow of disengaging it from the ratchet-wheel 1 upon a very slight movement 90 of the lever 13, the lever 13 is provided with an abutment 20, and a pin 41 is fixed to the back of the box 12 in such a manner that when the lever 13 is pulled toward the ratchet-wheel 1 the said pin comes into contact 95 with a curved lateral surface of the dog 17 and swings the latter on its pivot 14 against the pressure of spring 15 into the position shown in Fig. 3, so that the surface 19 of a recess 18 in the pawl is pressed against 100 the said abutment 20, and the dog 17 stands radial to the ratchet-wheel 1. When the levers 4, 8, and 13 are moved into their upper position by means of the cam 3, the curved lateral surface of the dog 17, losing the support 105 of the pin 41, is rotated by the spring 15 and is thrown out of engagement with the ratchet-wheel 1 during the initial rising movement of the lever 13. It is obvious that owing to this arrangement only a very slight 110 extension of the spring 21 and slight movement of levers 4, 8, and 13 are required in or-

der to disengage the dog 17 from the ratchet-wheel 1.

When the lever 13 is in its lower position, with the dog 17 engaging the ratchet-wheel 1, the rotation of the ratchet-wheel causes each tooth as it passes under the dog 17 to raise the dog and give a corresponding movement to the lever 13.

The ratchet-wheel 1 is turned by mechanism controlled by the distance traversed by the vehicle, or if the vehicle is at rest during hire the work of rotating the ratchet-wheel is taken by a clockwork. An air-pump (not shown) gives an air-pressure impulse at each revolution of the road-wheel to an air-piston 100, which operates a lever 101, carrying a dog 102 and retracted after each impulse by a spring 103. The dog 102 operates the ratchet-wheel 104, whence motion is conveyed by toothed wheels 105 106 to the prismatic shaft 107, carrying toothed wheel 108, which may be previously set to engage any one of the graduated set of tooth-wheels 109 on shaft 110 chosen, according to the diameter of the road-wheel. By beveled gear 111 and 112 motion passes to shaft 113 and wheel 114, which in the position illustrated in Fig. 7 meshes with wheel 115 on shaft 122, worm 123 engaging with worm-wheel 124 on shaft 125 of ratchet-wheel 1. Wheel 114 is shiftable by means of fork 120 and cam 121, moved by exterior lever 140, and can be moved out of gear with 115, or if moved farther will clutch with wheel 118 and give a different ratio of transmission through wheel 117, or by removing wheel 114 in the other direction it clutches with wheel 118, giving another ratio of transmission through wheel 119. Wheel 124 is loose on shaft 125 and carries a pawl 126, engaging a ratchet-wheel 127, fast to said shaft 125. When the vehicle is at rest, the wheel 124 ceases to revolve; but a clockwork 128, acting through wheel 129, loose on shaft 125, drives the latter through a pawl 130 and ratchet-wheel 131, fast to the shaft 125. The shaft 125 is thus when the taximeter is in action normally driven by the transmission mechanism from the road-wheel, and the ratchet-wheel 131 overruns the pawl 130; but when the vehicle stops or moves so slowly that the clockwork rating exceeds the pace of the vehicle the clockwork drives the shaft 125, and the ratchet-wheel 127 overruns the pawl 126.

On the lever 13 are two spring-pressed levers 22 59, pivoted at 23. The lever 22 is double-armed, the lower arm being marked 24. The upper end of lever 22 ends in a tooth 27; and in the raised position of lever 13 the tooth 27 extends under and lifts out of action the pawl 35.

When the lever 13 is moved toward the ratchet-wheel 1, the tooth 27 allows the pawl 35 to engage a ratchet-segment 31, integral with an arm 30, pivoted at 37, the said seg-

ment being simultaneously engaged by the said tooth. The lever 22 thus assumes the position shown in Fig. 2, in which its arm 24 bears against a fixed abutment 40 and is thus prevented from engaging a ratchet-wheel 25, mounted on an axle 42. This ratchet-wheel 25 serves for driving one of the counting-wheels, and the purpose of the segment 31 is to keep the lever 22 out of engagement with the said ratchet-wheel until the minimum-fare distance has been traversed or an equivalent amount of time has been consumed.

The rotation of the ratchet-wheel 1 by the means already indicated causes the lever 13 to be rocked on its pivot 11, and each movement of the said lever toward the segment 31 causes the latter to be displaced by means of the tooth 27, the segment being retained in its new position by the pawl 35. During the return movement of the lever 13 under the action of the spring 21 the tooth 27 trips over a certain number of teeth on the segment.

The tooth 27 after a certain number of rocking movements rides off the lower end of the segment 31; but the adjustment is such that at the end of the rocking movement by which this is accomplished the lever-arm 24 is still on the right-hand side of the stop 40. During the next rocking movement, however, the said lever-arm clears the said stop, so that the lever 22 is enabled to rotate on its pivot 23 under the influence of the spring by which it is actuated. The ratchet-wheel 25 is thus engaged by the lever-arm 24, and the abutment 40 then serves to prevent the said lever-arm from becoming disengaged from the said wheel by vibration or the like. The distance to be traversed or the amount of time to be consumed before the counting mechanism is started can be controlled by adjusting the segment 31. Assuming, for instance, that the wheel 1 rotates through an angle corresponding to one tooth-space while the vehicle traverses a distance of two hundred yards (which shall be called the "unit" distance) and that $n \times 200$ yards is the distance to be traversed before the counting mechanism comes into operation, the segment 31 is so adjusted that the tooth 27 is not disengaged therefrom until $n - 1$ displacements of the segment have been produced by the rocking of the lever 13. In the example illustrated the segment 31 is so adjusted that the counting mechanism is operated when a distance equal to twice the unit distance has been traversed by the vehicle, the segment 31 being rotated through an angle corresponding to two of its tooth-spaces by one rocking movement of the lever 13. This adjustment is such that when the vehicle starts the tooth 27 engages what may be called the "last" tooth-space on the segment, as shown in Fig. 2. The movement of the lever 13 while the first unit distance is being traversed causes the tooth 27 to be disengaged from

the segment 31; but the disengagement of the said tooth takes place while the lever 13 is moving away from the segment and too late to allow the arm 24 to clear the abutment 40. During the next movement of the lever 13, however, the said arm is enabled to clear the said abutment, and thus comes into engagement with the ratchet-wheel 25 at the moment when the minimum-fare distance—
 10 that is to say, twice the unit distance—has been traversed. The parts then occupy the positions indicated in Fig. 3, so that subsequent movements of the lever 13, due to rotation of the ratchet-wheel 1, cause the ratchet-wheel 25 to be operated by means of the arm 24. If more than twice the unit distance is to be traversed by the vehicle before the counting mechanism is started, the adjustment of the segment 31 is suitably altered by rotating a cam-disk 38, mounted on pin 39, which serves as abutment for an arm 78, integral with the arm 30, by which the segment is supported. The cam-disk is rotated by a suitable key and is accessible for that purpose only when the case 12 is opened. The ratchet-wheel 25 is fixedly connected with a number-wheel 26, the numerals of which may represent cents, the axle 42 of the said ratchet-wheel being stepped in a suitable bearing situated at the center of the ring 49, already referred to. The one end of the said axle is supported by a suitable bearing formed in a bar 43, extending across the number-wheel 26. A spring-box 44 is arranged within the ring 49, and one end of the spring contained in the said box is inserted into a slot in the axle 42 in such a manner that the rotation of the axle with the wheels 25 and 26 by the lever 22 is not prevented by the said spring, but that the latter rotates the said axle and wheels back to their original positions, when the lever-arm 24 is disengaged from the wheel 25. The rotation of the axle 42 by the said spring is limited by a catch 47, which is fixed to a spring 48, Figs. 5 and 6, and extends into the path of a projecting pin 46, fixed to a disk 45, integral with the wheel 25. The said catch 47 is so shaped that it can be tripped by the pin 46 during the rotation of the wheel 25 by the lever-arm 24. The numerals representing dollars are placed on a wheel 50, which is fixed to a hollow axle 54, mounted on a sleeve 56, which surrounds the axle 42.
 15 55 A ratchet-wheel 55, fixed to the axle 54, is adapted to be operated by means of a tooth at the end of the spring-pressed lever 59, already referred to, the said lever 59 being connected at 23 with the rocking lever 13. A projection 60 at the free end of the lever 59 bears against the circumference of the disk 45, and the diameter of the latter is such that the tooth on the said lever can only engage the wheel 55 when the said projection 60 extends into a recess 62, with which the disk 45

is provided. One wall of this recess is inclined in such a manner as to displace the projection 60 and disengage the lever 59 from the wheel 55 when the latter has been rotated through an angle corresponding to one tooth-space. The wheel 55 is therefore rotated through this angle during each complete revolution of the wheel 25.

A spring-box 52, carried by a support 51 and containing a spring 53, surrounds the axle 54, one end of the spring 53 being attached to the latter in such a manner that the axle 54, with the wheels 55 and 50, is rotated back to its original position when the driving mechanism is disconnected from the counting mechanism. The rotation of the wheel 50 by the spring 53 is limited by means of an abutment 58, fixed to the said wheel and adapted to come into contact with a suitable stop. Two spring-actuated bell-crank levers 65 and 65', mounted on an axle 63, normally lock the ratchet-wheels 25 and 55, respectively, the said levers being disengaged from the said wheels during the movement of the levers 4, 8, and 13 by means of a projecting rod 66, which is fixed to the lever 8 and abuts against the curved arms 67 and 67' of the bell-crank levers. The reliability of the counting mechanism is thus further increased.

When the lever-arm 24 clears the abutment 40, the movement of the lever 22 causes a rearward projection of the tooth 27 to engage a ratchet-wheel 28, Fig. 4, so that the subsequent rocking of the lever 13 causes anti-clockwise rotation to be imparted to the said ratchet-wheel 28. The latter is adapted to drive a series of controlling-wheels 29, 29', and 29''. Clockwise rotation of the ratchet-wheel 28 is prevented by means of a pawl 64.

In order to readjust the counting mechanism in the position shown in Fig. 1 when the levers 4, 8, and 13 have been moved into their position of out of action by means of the cam 3, the pawl 35 must be disengaged from the segment 31 and the lever 22 must be so operated that during the movement of the lever 13 toward the segment the tooth 27 clears the latter and abuts against the said pawl. For this purpose the lever-arm 24 is provided with a curved projection 33, so arranged that when the said lever-arm engages the wheel 25 the said projection abuts against a pin 32, fixed to the lever 8. The operation of the latter by means of the cam 3 and lever 4 therefore causes the lever 22 to be operated in the manner desired.

What I claim as my invention, and desire to secure by Letters Patent of the United States, is—

1. In a fare-indicator the combination with an operating-wheel and counting mechanism, of means for operating said counting mechanism from the operating-wheel comprising a rocking lever normally drawn toward the operating-wheel, means for limiting

the movement of said lever, a dog pivoted on said lever and adapted to be swung into a position to engage said operating-wheel and means for holding said dog in its operative position when the rocking lever is in coöperation with the operating-wheel.

2. In a fare-indicator the combination with an operating-wheel and counting mechanism, of means for operating said counting mechanism from the operating-wheel comprising a rocking lever normally drawn toward the operating-wheel, means for limiting the movement of said lever, a dog pivoted on said lever a spring for throwing said dog out of engaging position and a fixed stop for swinging the dog into engaging position as the rocking lever approaches the operating-wheel.

3. In a fare-indicator the combination with an operating-wheel and counting mechanism, of means for operating said counting mechanism from the operating-wheel comprising a rocking lever normally drawn toward the operating-wheel, means for limiting the movement of said lever, a dog pivoted on said lever and adapted to engage said operating-wheel, means for locking said dog in its operative position and a double-armed lever also pivoted to the rocking lever and in indirect connection with the counting mechanism, substantially as described.

4. In a fare-indicator the combination with an operating-wheel and counting mechanism, of means for operating said counting mechanism from the operating-wheel comprising a rocking lever normally drawn toward the operating-wheel, means for limiting the movement of said lever, a dog pivoted on said lever and adapted to engage said operating-wheel, means for locking said dog in its operative position and a double-armed lever also pivoted to the rocking lever and in indirect connection with the counting mechanism and means for throwing said counter-operating mechanism with small movement thereof out of gear with the operating-wheel comprising a pair of pivoted coating levers adapted to act on the rocking lever, a cam operating said levers and means for holding the dog aforesaid out of engagement with the operating-wheel.

5. In a fare-indicator the combination with an operating-wheel and counting mechanism of means for operating said counting mechanism from the operating-wheel comprising a rocking lever normally drawn toward the operating-wheel, a pawl pivoted on said lever and adapted to engage said operating-wheel, an abutment for locking said pawl in its operative position and a double-armed lever also pivoted to the rocking lever and adapted to indirectly actuate the counting mechanism; means for throwing said counter-operating mechanism with small movement thereof

out of gear with the operating-wheel comprising a pair of pivoted coating levers adapted to act on the rocking lever, a cam operating said levers and means for holding the pawl aforesaid out of engagement with the operating-wheel and means for holding said double-armed lever out of engagement with the counting mechanism until the operating-wheel has made a predetermined movement comprising an adjustable toothed segment adapted to be operated by said double-armed lever and a catch adapted to hold said segment in the position given it by said lever substantially as described.

6. In a fare-indicator the combination with an operating-wheel and counting mechanism of means for operating said counting mechanism from the operating-wheel comprising a rocking lever normally drawn toward the operating-wheel, a dog pivoted on said lever and adapted to engage said operating-wheel an abutment for locking said dog in its operative position and a double-armed lever also pivoted to the rocking lever and adapted to indirectly actuate the counting mechanism; means for throwing said counter-operating mechanism with small movement thereof out of gear with the operating-wheel comprising a pair of pivoted coating levers adapted to act on the rocking lever, a cam operating said levers and means for holding the dog aforesaid out of engagement with the operating-wheel, means for holding said double-armed lever out of engagement with the counting mechanism until the operating-wheel has made a predetermined movement comprising an adjustable toothed segment adapted to be operated by said double-armed lever and a catch adapted to hold said segment in the position given it by said lever and means for returning the counter-operating mechanism to its original position comprising a projection on the aforesaid double-armed lever and a fixed abutment coating with said projection substantially as described.

7. In a fare-indicator the combination with an operating-wheel and counting mechanism of means for operating said counting mechanism from the operating-wheel comprising a rocking lever normally drawn toward the operating-wheel, a dog pivoted on said lever and adapted to engage said operating-wheel an abutment for locking said dog in its operative position and a double-armed lever also pivoted to the rocking lever and adapted to indirectly actuate the counting mechanism; means for throwing said counter-operating mechanism with small movement thereof out of gear with the operating-wheel means for holding said double-armed lever out of engagement with the counting mechanism until the operating-wheel has made a predetermined movement comprising an adjustable

toothed segment adapted to be operated by said double-armed lever and a catch adapted to hold said segment in the position given it by said lever, means for returning the counter-operating mechanism to its original position comprising a projection on the aforesaid double-armed lever and a fixed abutment co-acting with said projection and means for returning the counting mechanism to zero

when disengaged from its operating mechanism.

In witness whereof I have signed this specification in the presence of two witnesses.

GUSTAV BAUM.
